UNITED STATES PATENT OFFICE.

GEORG GRABE, OF NIKOLASSEE, NEAR BERLIN, GERMANY, ASSIGNOR TO SIEMENS & HALSKE A. G., OF BERLIN, GERMANY, A CORPORATION OF GERMANY.

APPARATUS FOR METERING CONVERSATIONS IN AUTOMATIC TELEPHONE-EXCHANGES.

1,020,976.

Specification of Letters Patent. Patented Mar. 26, 1912.

Application filed July 28, 1910. Serial No. 574,257.

To all whom it may concern:

Be it known that I, GEORG GRABE, a subject of the German Emperor, and residing at Nikolassee, near Berlin, Germany, have 5 invented certain new and useful Improvements in Apparatus for Metering Conversations in Automatic Telephone-Exchanges, of which the following is a specification.

This invention relates to apparatus for 10 metering conversations in automatic telephone exchanges, in which the metering takes place after the termination of the conversation. In contradistinction to former arrangements, in which the selectors and 15 connectors utilized for a connection are released simultaneously with the metering of the conversation, according to my invention the release of the connectors and selectors is retarded or takes place only after metering 20 has been effected. To this end, at the termination of the conversation after the line relay located at the connector has become currentless or has operated, a connection is brought about which causes the first selector 25 first to meter at the calling subscriber's line by means of an additional change over, and then by means of a subsequent reversal to bring about the releases of the selectors and the connector occupied for the connection. 30

According to my invention the testing and releasing lines are closed backward up to the first selector in succession by way of the coils of the auxiliary relay as soon as the line 35 relay of one of the speaking subscribers located at the connector has become currentless and without a releasing relay being actuated or a relay which serves at the first selector for influencing the meter of the calling station by way of another branch of the connecting line closed in the meantime at the connector, whereupon the connector is released by interrupting the testing line to the second selector at the first selector and 40 by interrupting the testing lines in turn by means of the auxiliary relays. This is brought about, according to my invention, by the side or controlling switch of the connector being placed one step beyond the 45 through position after the line relay of the calling or called subscriber located at the connector has become currentless. In this position the testing line leading from the connector to the last selector is closed by 50 way of the winding of an auxiliary relay

which interpolates the electromagnet of the side or controlling switch in a holding circuit, the testing relay of the last selector closes the testing line to the preceding selector in the row by way of the coil of a like auxiliary relay, and so on until the testing relay of the first selector connects in circuit the controlling switch electromagnet by way of an interrupter. Then the controlling switch at the first selector will be brought 60 one step forward and arrives into a position, in which a relay at the first selector for starting the movement of the meter of the subscribers' lines is energized by way of a branch line closed at the connector. Owing 65 to the controlling switch at the first selector being automatically fed forward a second time, the testing line to the second selector is now interrupted and the stepwise interruption of the testing lines and the further 70 movement of the controlling switch of the connectors for interpolating the circuits of the releasing magnets are brought about by means of the auxiliary relays. 75

In order after metering has taken place, 80 and the releasing circuits at the controlling switches have been interpolated, to prevent the connector being advanced when the telephone is hung up at the calling station only, and to prevent the first selector in the row 85 being advanced when the telephone is hung up only at the called station, according to my invention the calling subscriber's line relay which is located at the connector and when currentless brings about the interpolation 90 of the releasing circuit is connected by the controlling switch into a holding circuit, while the line relay at the first selector is connected to the calling line. 95

One illustrative embodiment of my invention is represented diagrammatically by way of example in the accompanying drawing.

Referring to the drawing, 133 designates a calling station which is connected with a called station 2655 by way of the pre-selector VW^s , two selectors GW^1 and GW^2 and the connector LW . In the drawing the selectors and connector are shown in the position during the conversation, only those parts of the connection and apparatus being shown, for the sake of clearness, which are requisite for understanding the connection of the releasing and metering circuits at the known pre-selectors and Strowger selectors. 105 110

The coil 1 of the testing and disconnecting relay TR^{33} at the pre-selector VW^{33} is interpolated for the duration of the connection in a holding circuit by way of the testing line c^1 of the selector GW^1 and holds the branches a^{133}, b^{133} connected with the branches a^1, b^1 by way of the contacts t^1, t^2 and the contact arms o^1, o^2 of the selector GW^1 . The meter ZR^{33} is connected 5 in shunt with the coil 1 of the relay TR^{33} and the current flowing from the + pole of the exchange battery by way of the contact n^1 of the releasing magnet N , series resistances w^1, w^2 , testing line c^1 , contact arm o^3 , coil 1 of relay TR^{33} and coil of meter ZR^{33} , contact t^3 , contact i^1 of the pulling switch does not suffice, on the one hand, for 10 energizing the meter magnet and produces, on the other hand, a fall of voltage at the testing line c^1 which makes this appear occupied, as another subscriber's relay TR testing with its high resistance coil 2 on this line cannot obtain sufficient current to excite it. At the selector GW^1 the levers s of 15 the controlling switch are in the fifth, i. e. the through position, in which the branches a^1, b^1 are connected with the branches a^2, b^2 of the selector GW^2 by way of the levers s^1, s^2 of the controlling switch and the selector 20 arms o^4, o^5 , while the line relays A, B, X are disconnected from the branch line. The low resistance coil 1 of the testing relay P of the selector GW^1 is here connected by 25 way of the switch levers s^3, s^4 and the selector arm o^6 to the test line c^2 , which is connected with the coil of an auxiliary relay Q^1 at the selector GW^2 by way of a series resistance w^3 and the switch lever s^{12} of the controlling switch of the second selector 30 GW^2 . The relays P and Q^1 are currentless, however, as the circuit is broken in the through position at the armature of the testing relay P^1 .

At the selector GW^2 the controlling switch 35 levers are in the fourth position, which is likewise the through position, and the branch lines a^2, b^2 are connected with the branch lines a^1, b^1 leading to the connector LW by way of the switches s^8, s^9 of the controlling 40 switch and the selector arms o^7, o^8 , while the line relays A^1, B^1, X^1 of this selector are disconnected. The low resistance coil 1 of the testing relay P^1 is connected by way of the switches s^{11}, s^{10} and the selector arm o^9 45 with the test line c^3 which, however, is interrupted at the switch s^{10} of the controlling switch of connector LW . At the connector LW the controlling switch is in the sixth or through position, and the branch lines a^3, b^3 are connected by way of the switches s^{15}, s^{16} , the condensers k^1, k^2 and the selector arms o^{10}, o^{11} with the branch lines a^{55}, b^{55} which lead to the subscriber's station 50 2655.

The line relays A^2, B^2, X^2 are connected 55 in front of the condensers k^1, k^2 located in

the branches of the telephone line in bridge connection with the branch lines a^3, b^3 , and the choking coil Dr and the supervisory relay Y are connected behind the condensers in bridge connection with the branch lines a^{55}, b^{55} . The coils 1, 2 of the relay TR^{55} of the called subscriber 2655 are energized for the duration of the connection by way of the switch s^{17} , connector arm o^{12} , line c^{55} and series resistance w^5 and hold the line relay 60 of the subscriber disconnected from the branch lines a^{55}, b^{55} ; simultaneously, line c^{55} is subjected to a testing voltage which prevents the connection of a second connector to the line of the subscriber 2655. 80

The microphone current for the subscriber flows from the + pole of the battery by way of relay B^2 , coil 1 of the differential relay X^2 , branch line b^3 , selector arm o^8 , switch lever s^9 , branch line b^2 , selector arm o^5 , switch lever s^2 , branch line b^1 , pre-selector arm o^2 , contact t^2 , branch line b^{133} , station 133, branch line a^{133} , contact t^1 , pre-selector arm o^1 , branch line a^1 , switch lever s^1 , selector arm o^4 , branch line a^2 , switch lever s^8 , selector arm o^7 , branch line a^3 , coil 2 of the relay X^2 , relay A^2 and back to the battery. The feeding current for the subscriber 2655 flows from the + pole of the battery by way of relay Y , switch lever s^{16} , connector arm o^{11} , branch line b^{55} , station 2655, branch line a^{55} , connector arm o^{10} , switch lever s^{18} , choking coil Dr and back to the battery. Consequently, the relays A^2, B^2, Y are energized during the conversation, but not the differential relay X^2 because the two coils 1, 2 oppose one another. 90

As soon as the calling or the called subscriber hangs up his telephone, owing to the relay B^2 or Y , respectively, becoming currentless the electromagnet S^2 of the controlling switch is connected by way of switch lever s^{20} in position 6, contact b^2 of the relay B^2 or contact y of the relay Y , in a circuit leading from the battery by way of the interrupter U . In this manner the controlling switch is brought from the sixth into the seventh position. In this position the branch line a^3 is disconnected at the switch s^{15} from the branch line a^{55} and connected by way of the coil of the relay B^2 with the + pole of the battery, so that a current now flows from the + pole of the battery by way of relay B^2 , switch lever s^{15} , coil 2 of the differential relay X^2 and relay A^2 to the - pole of the battery, while the test line c^3 is connected at the switch s^{10} with the coil of the relay Q^2 . Another current arises, which flows from the + pole of the battery by way of switch lever s^{11} , coil 1 of the relay P^1 , switch lever s^{10} , selector arm o^9 , test line c^3 , resistance w^4 , switch lever s^{10} , relay Q^2 to the - pole of the battery which energizes the relays Q^2 and P^1 , there being 120 at the test line c^3 a fall of voltage which pre- 130

vents the excitation of a relay P^1 of another second selector testing in known manner with the high resistance coil 2. The relay Q^2 interpolates the electromagnet S^2 at the 5 contact q^2 in a holding circuit, while by closing the contact p^1 the relay P^1 causes a current to flow from the + pole of the battery by way of the switch lever s^3 , coil 1 of relay P , switch lever s^4 , selector arm o^6 , 10 test line c^2 , resistance w^3 , switch lever s^{12} , relay Q^1 , contact p^1 to the - pole of the battery. The relay Q^1 interpolates at its contact q^1 the electromagnet S^1 of the controlling switch at the selector GW^2 in a 15 holding circuit, while the relay P connects the electromagnet S of the first selector at the contact p to the battery by way of the interrupter U . After the circuit has been closed and subsequently opened at the in- 20 terrupter U the controlling switch at the first selector is moved on from the fifth into the sixth position. In this position the relay Z connected with the - pole is connected by way of the switch s^6 to the branch 25 line a^2 , while the branch lines a^1, b^1 are connected again with the line relays A, B, X by way of the switches s^1 and s^2 . A current flows from the + pole of the battery by way of the coil of the relay B^2 at the connector 30 LW , switch lever s^{15} in position 7, branch line a^3 , selector arm o^7 , switch lever s^8 , branch line a^2 , selector arm o^4 , switch lever s^6 , relay Z to the - pole of the battery. The current flowing to the - pole of the battery 35 from the branch line a^3 by way of the coils of the relays X^2, A^2 is only small on account of the high resistance of these relay coils in comparison with that of the coil of the relay Z . By attracting its armature the 40 relay Z short circuits the series resistance w^1 , so that a heavy current flows from the + pole of the battery by way of the contact z , resistance w^2 , test line c^1 , pre-selector arm o^4 , the coils of the meter ZR^{33} and re- 45 lay TR^{33} connected in parallel, contacts t^3, i^1 to the - pole of the battery, so that the meter of subscriber 133 is fed forward. Further, in the sixth position of the control- 50 ling switch the electromagnet S is connect- ed directly with the interrupter U and when the circuit at the interrupter is next closed and opened the controlling switch is brought by the electromagnet S from the sixth into the seventh position. In this 55 position the releasing electromagnets M and N of the first selector GW^1 and the controlling switch of the latter are connected at the switch s^7 with the rest contact of the relay B and they are interpolated as soon 60 as no current flows over the subscriber's line.

Further, in the seventh position of the controlling switch the test line c^2 is interrupted at the switch s^4 and the relay Q^1 65 which has consequently become currentless

interrupts the current in the electromagnet S^1 , whereby the controlling switch of the second selector GW^2 is moved from the fourth into the fifth position, in which the releasing electromagnets M^1 and N^1 are in- 70 terpolated at the switch s^{14} and the line c^3 is interrupted at the switch s^{10} .

The relay Q^2 which has become current- less owing to the interruption of the line c^3 interrupts the current in the electromagnet S^2 , whereupon the controlling switch of the connector passes from the seventh 75 into the eighth position, in which the releasing electromagnets M^2, N^2 of the connector LW and the controlling switch of the latter are interpolated at the switch s^{21} . As the relay B^2 is interpolated in a holding circuit leading from the + pole of the battery by way of the relay B^2 , switch lever s^{15} , coil 2 of the differential relay X^2 and relay 80 A^2 to the - pole of the battery and holds the contact b^2 open, when the controlling switch is in the seventh and eighth positions, the circuit of the releasing electro- 85 magnets M^2, N^2 can only be closed at the connector LW when the called subscriber 90 2655 has hung up his receiver and the relay Y , which has thereby become currentless, has closed the contact y .

When their armatures are attracted the 95 releasing electromagnets N, N^1, N^2 are connected together with the electromagnets M, M^1, M^2 into holding circuits which are only disconnected when the selectors open the pressing contacts l, l^1, l^2 , after reaching 100 their rest position. The releasing magnet N of the first selector GW^1 also brings about the interruption of the line c^1 at the contact n^1 , whereby the relay TR^{33} also becomes currentless and, owing to its armature fall- 105 ing, connects the rotatory electromagnet D^{33} of the pre-selector VW^{33} to the battery by way of the interrupter U^1 , contact r^2 of the line relay R^{33} , contact t^4 , contact i^1 , whereby the pre-selector is rotated step by step until 110 it arrives into its rest position, in which the contact i^1 is opened and electromagnet D^{33} is cut out of circuit.

I claim:—

1. In an automatic telephone system, the 115 combination, with subscribers' stations, a telephone and switching means in each subscriber's station, an exchange, lines for connecting the subscribers' stations with the exchange, selectors and connectors for connecting a calling with a called station and testing branches for connecting the selectors with each other, releasing relays at the selectors and connectors, a meter for each subscriber's station, and means for connecting 120 and for starting the meter through the testing branch, of relays at the connector controlling the calling and called lines, switching devices at a selector for making 125 a circuit for the meter of the calling sub- 130

scriber at the end of a conversation, switch armatures at said relays at the connector which are moved when the telephone is replaced at a subscriber's station, means for imparting the switching movements of said armatures to the switching devices at the selectors, and means at the switching devices for closing the circuits for the releasing relays of the selectors and connectors 10 after the meter circuits have been made.

2. In an automatic telephone system, the combination, with subscribers' stations, a telephone and switching means in each subscriber's station, an exchange, lines for connecting the subscribers' stations with the exchange, a calling device in the exchange for each subscriber, selectors and connectors for connecting a calling with a called station and testing branches for connecting the selectors with each other, a controlling switch at each selector and connector for bringing about the stepwise change over of the selector circuits requisite for operating the selectors, releasing relays at the selectors and connectors a meter for each subscriber, and means for connecting and for starting the meter through the testing branch, of relays at the connector controlling the calling and called lines, switching devices at a selector for 25 making a circuit for the meter of the calling subscriber at the end of a conversation, switch armatures at said relays at the connector which are moved when the telephone is replaced at a subscriber's station, means 30 for imparting the switching movements of said armatures to the switching devices at the selectors, and means at the switching devices for closing the circuits for the releasing relays of the selectors and connectors 40 after the meter circuits have been made.

3. In an automatic telephone system, the combination, with subscribers' stations, a telephone and switching means in each subscriber's station, an exchange, lines for connecting the subscribers' stations with the exchange, a calling device in the exchange for each subscriber, selectors and connectors for connecting a calling with a called station and testing branches for connecting the selectors 45 with each other, a controlling switch at each selector and connector for bringing about the stepwise change over of the selector circuits requisite for operating the selectors, releasing relays at the selectors and connectors, a meter for each subscriber, and means for connecting and for starting the meter through the testing branch, of relays at the connector controlling the calling and called lines, switching devices at a selector for 50 making a circuit for the meter of the calling subscriber at the end of a conversation, switch armatures at said relays at the connector which are moved when the telephone is replaced at a subscriber's station, means 55 comprising switch arms at the controlling 60

switches of the selectors for imparting the switching movements of said armatures to the switching devices at the selectors, and means at the switching devices for closing the circuits for the releasing relays of the 70 selectors and connectors after the meter circuits have been made.

4. In an automatic telephone system, the combination, with subscribers' stations, a telephone and switching means in each subscriber's station, an exchange, lines for connecting the subscribers' stations with the exchange, a calling device in the exchange for each subscriber, selectors and connectors for connecting a calling with a called station 80 and testing branches for connecting the selectors with each other, a controlling switch at each selector and connector for bringing about the stepwise change over of the selector circuits requisite for operating the selectors, releasing relays at the selectors and connectors, a meter for each subscriber, and means for connecting and for starting the meter through the testing branch, of relays at the connector controlling the calling and 85 called lines, switching devices at the first selector in the row for making a circuit for the meter of the calling subscriber at the end of a conversation, switch armatures at said relays at the connector which are moved when the telephone is replaced at a subscriber's station, means comprising switch arms at the controlling switches of the selectors for imparting the switching movements of 90 said armatures to the switching devices at the selectors, means at each connector and at each first selector in the row for moving the controlling switches another step in succession after the termination of a conversation, means at the remaining selectors for 95 locking their controlling switches until metering has taken place, means at the selectors and at each connector for releasing the latter locked controlling switches after the meter circuits have been made, and means 100 at the switching devices for closing the circuits for the releasing relays of the selectors and connectors after the meter circuits have been made.

5. In an automatic telephone system, the combination, with subscribers' stations, a telephone and switching means in each subscriber's station, an exchange, lines for connecting the subscribers' stations with the exchange, a calling device in the exchange for each subscriber, selectors and connectors for connecting a calling with a called station, testing lines and testing relays for connecting the selectors with one another, with the connector and with the subscribers' stations, a controlling switch at each selector and connector for bringing about the stepwise change over of the selector circuits requisite for operating the selectors, releasing relays at the selectors and connectors, a meter for 115 120 125 130

each subscriber, and means for connecting and for starting the meter through the testing branch, of relays at the connector controlling the calling and called lines, switching devices at the first selector in the row for making a circuit for the meter of the calling subscriber at the end of a conversation, switch armatures at said relays at the connector which are moved when the telephone is replaced at a subscriber's station, means comprising switch arms at the controlling switches of the selectors for imparting the switching movements of said armatures to the switching devices at the selectors, an auxiliary relay at each connector and at each selector, with the exception of the first selector in a row, in series with the testing line and the testing relay of the previous selector, switching means controlling the testing lines, testing relays and auxiliary relays for moving the controlling switches another step in succession after the termination of a conversation, the auxiliary relays being used for locking the connectors and the selectors with the exception of the first selector in a row until metering has taken place, means at the selectors and at each connector for releasing the latter locked controlling switches after the meter circuits have been made, and means at the switching devices for closing the circuits for the releasing relays of the selectors and connectors after the meter circuits have been made.

6. In an automatic telephone system, the combination, with subscribers' stations, a telephone and switching means in each subscriber's station, an exchange, lines for connecting the subscribers' stations with the exchange, a calling device in the exchange for each subscriber, selectors and connectors for connecting a calling with a called station, testing lines and testing relays for connecting the selectors with one another, with the connectors and with the subscribers' stations, a controlling switch at each selector and connector for bringing about the step-wise change over of the selector circuits requisite for operating the selectors, releasing relays at the selectors and connectors, a meter for each subscriber, and means for connecting and for starting the meter through the testing branch, of relays at the connector controlling the calling and called lines, switching devices at the first selector in the row for making a circuit for the meter of the calling subscriber at the end of a conversation, switch armatures at said relays at the connector which are moved when the telephone is replaced at a subscriber's station, means comprising switch arms at the controlling switches of the selectors for imparting the switching movements of said armatures to the switching devices at the selectors, an auxiliary relay at each connector and at each selector, with the exception of the first selector in a row, in series with the testing line and the testing relay of the previous selector, switching means controlling the testing lines, testing relays and auxiliary relays for moving the controlling switches another step in succession after the termination of a conversation, means for connecting the auxiliary relay of a connector in a holding circuit after the first step of the appertaining controlling switch beyond the through position, means for connecting the auxiliary relay of the first selector in a row with the subscribers' lines after the first step of the appertaining controlling switch, means for locking the controlling switches of the selectors except the first selector in a row, in series with the testing line and the testing relay of the previous selector, switching means controlling the testing lines, testing relays and auxiliary relays for moving the controlling switches another step in succession after the termination of a conversation, the auxiliary relays being used for locking the connectors and the selectors with the exception of the first selector in a row until metering has taken place, means at the selectors and at each connector for releasing the latter locked controlling switches after the meter circuits have been made, and means at the switching devices for closing the circuits for the releasing relays of the selectors and connectors after the meter circuits have been made.

7. In an automatic telephone system, the combination, with subscribers' stations, a telephone and switching means in each subscriber's station, an exchange, lines for connecting the subscribers' stations with the exchange, a calling device in the exchange for each subscriber, selectors and connectors for connecting a calling with a called station, testing lines and testing relays for connecting the selectors with one another, with the connectors and with the subscribers' stations, a controlling switch at each selector and connector for bringing about the step-wise change over of the selector circuits requisite for operating the selectors, releasing relays at the selectors and connectors, a meter for each subscriber, and means for connecting and for starting the meter through the testing branch, of relays at the connector controlling the calling and called lines, switching devices at the first selector in the row for making a circuit for the meter of the calling subscriber at the end of a conversation, switch armatures at said relays at the connector which are moved when the telephone is replaced at a subscriber's station, means comprising switch arms at the controlling switches of the selectors for imparting the switching movements of said armatures to the switching devices at the selectors, an auxiliary relay at each connector and at each selector, with the exception of the first selector in a row, in series with the testing line and the testing relay of the previous selector, switching means controlling the testing lines, testing relays and auxiliary relays for moving the controlling switches another step in succession after the termination of a conversation, means for connecting the auxiliary relay of a connector in a holding circuit after the first step of the appertaining controlling switch beyond the through position, means for connecting the auxiliary relay of the first selector in a row with the subscribers' lines after the first step of the appertaining controlling switch, means for locking the controlling switches of the selectors except the first selector in a row, in series with the testing line and the testing relay of the previous selector, switching means controlling the testing lines, testing relays and auxiliary relays for moving the controlling switches another step in succession after the termination of a conversation, the auxiliary relays being used for locking the connectors and the selectors with the exception of the first selector in a row until metering has taken place, means at the selectors and at each connector for releasing the latter locked controlling switches after the meter circuits have been made, and means at the switching devices for closing the circuits for the releasing relays of the selectors and connectors after the meter circuits have been made.

ing the first in the row until the metering has occurred, means at the selectors and at each connector for releasing said locked controlling switches after the meter circuits 5 have been made, and means at the switching devices for closing the circuits for the releasing relays of the selectors and connectors after the meter circuits have been made.

8. In an automatic telephone system, the 10 combination, with subscribers' stations, a telephone and switching means in each subscriber's station, an exchange, lines for connecting the subscribers' stations with the exchange, a calling device in the exchange for 15 each subscriber, selectors and connectors for connecting a calling with a called station, testing lines and testing relays for connecting the selectors with one another, with the connectors and with the subscribers' stations, a controlling switch at each selector and connector for bringing about the step- 20 wise change over of the selector circuits requisite for operating the selectors, releasing relays at the selectors and connectors, a meter 25 for each subscriber, and means for connecting and for starting the meter through the testing branch, of relays at the connector controlling the calling and called lines, switching devices at the first selector in the 30 row for making a circuit for the meter of the calling subscriber at the end of a conversation, switch armatures at said relays at the connector which are moved when the telephone is replaced at a subscriber's station, 35 means comprising switch arms at the controlling switches of the selectors for imparting the switching movements of said armatures to the switching devices at the selectors, an auxiliary relay at each connector and at each selector, with the exception of the first selector in a row, in series 40 with the testing line and the testing relay of the previous selector, switching means controlling the testing lines, testing relays 45 and auxiliary relays for moving the controlling switches another step in succession after the termination of a conversation, means at the remaining selectors for locking their controlling switches until metering has 50 taken place, means at the selectors and at

each connector for releasing the latter locked controlling switches after the meter circuits have been made, means for moving the controlling switch of the first selector in a row another step for starting the progressive release of the selectors and the appertaining connector, and means at the switching devices for closing the circuits for the releasing relays of the selectors and connectors after the meter circuits have been made. 55

9. In an automatic telephone system, the combination, with subscribers' stations, a telephone and switching means in each subscriber's station, an exchange, lines for connecting the subscribers' stations with the exchange, a calling device in the exchange for 60 each subscriber, selectors and connectors for connecting a calling with a called station, a controlling switch at each selector and connector for bringing about the stepwise 65 change over of the selector circuits requisite for operating the selectors, releasing relays at the selectors and connectors, a meter for each subscriber, and means for connecting and for starting the meter through the testing branch, of relays at each connector having one pole connected to the same branch of the subscriber's line, condensers interpolated in the subscribers' lines between the 70 relays for dividing the latter into two 75 groups, switching devices at a selector for making a circuit for the meter of the calling subscriber at the end of a conversation, switch armatures at said relays at the connector which are moved when the telephone 80 is replaced at a subscriber's station, means for imparting the switching movements of 85 said armatures to the switching devices at the selectors, and means at the switching devices for closing the circuits for the releasing relays of the selectors and connectors 90 after the meter circuits have been made.

In testimony whereof I have signed my name to this specification in the presence of two witnesses.

GEORG GRABE.
